DESIGN FOR A WOVEN ELASTIC FABRIC

Howard F. Lord, Stoughton, Mass., assignor to
J. W. Wood Elastic Web Co., Stoughton, Mass.,
a corporation of Massachusetts

Application November 4, 1938, Serial No. 80,875

Term of patent 7 years

To all whom it may concern:

Be it known that I, Howard F. Lord, a citizen of the United States, residing at Stoughton, in the county of Norfolk and State of Massachusetts, have invented a new, original, and ornamental Design for a Woven Elastic Fabric, of which the following is a specification, reference being had to the accompanying drawing, forming part thereof.

The figure of the drawing is a top plan view on an enlarged scale of the woven elastic fabric

showing my design, which is characterized by successive longitudinal and transverse rows of small diamond-shaped figures, the center of each diamond in every other longitudinal row and in every other transverse row embodying exposed portions of additional threads, crossing said designated figures transversely, as shown.

I claim:

The ornamental design for a woven elastic fabric, as shown and described.

HOWARD F. LORD.
